INVENTOR
CHARLES LIONEL MARCUS

BY

Maxine Spinkster
ATTORNEY

UNITED STATES PATENT OFFICE.

CHARLES LIONEL MARCUS, OF NEW YORK, N. Y.

VANITY CASE.

Application filed May 21, 1923. Serial No. 640,296.

To all whom it may concern:

Be it known that CHARLES LIONEL MARCUS, citizen of the United States, residing at New York city, in the county of New York and State of New York, has invented certain new and useful Improvements in Vanity Cases, of which the following is a specification.

This invention relates to vanity cases. 10 More particularly it is directed to a vanity case of the character described in my co-pending application Serial No. 625,902, filed in the United States Patent Office on the 17th day of March 1923, in which provision is made, however, for holding a plurality of cosmetics.

One object of the invention is to provide a device of the character described which shall be exceedingly simple in construction, 20 neat in appearance, and highly efficient for the purposes described.

Other objects of this invention will in part be obvious and in part hereinafter pointed out.

25 Certain features herein shown and described are shown, described and claimed in my co-pending application aforementioned and accordingly are not claimed herein.

30 With the above exception the invention accordingly consists in the features of construction, combinations of elements and arrangement of parts which will be exemplified in the construction hereinafter described and of which the scope of application will be indicated in the following claims.

35 In the accompanying drawing, in which is shown one of various possible illustrative embodiments of this invention,

Fig. 1 is a perspective view of a vanity case embodying the invention shown in open position with the powder puff removed;

45 Fig. 2 is a cross-sectional view taken along line 2-2 of Fig. 1; and

Fig. 3 is a perspective view of the insert for shielding the contents of the container.

50 Referring in detail to the drawing, the vanity case there shown comprises a container or receptacle member 10 in which are held a plurality of cosmetics. In the form shown in the drawing, the container is adapted for two cosmetics, one a compact face powder 11 and the other a rouge

12, preferably also in compact form. 13 indicates the cover member for the container which may be spring-hinged to the container or otherwise suitably secured thereto so as to snugly close upon the container and cover the same. On the interior face of the cover is held a mirror 15.

The cosmetics such as 11 and 12 are firmly held, as by cement or glue or other suitable means, to the bottom of the container and are preferably of a height somewhat less than the height of the container. For shielding the interior of the container so as to prevent dirt or other foreign matter from entering the portion thereof occupied by the cosmetics, I provide a guard member 16 preferably of light sheet material such as celluloid or the like material, shaped so as to provide a top face 17 of dimensions substantially equal to the interior dimensions of the container so as to completely cover the contents thereof, and having side and end portions 18, 19, downturned from said face members and substantially at right angles thereto so as to fit snugly on the interior of the container against the corresponding walls thereof. For making the cosmetics accessible through said guard member, the face portion 16 is cut out or recessed as at 20, 21, thus permitting the corresponding cosmetic 11, 12 to show through said openings and be reached therethrough.

55 In the form shown in the drawing, the opening 20 is larger than the opening 21 since a larger portion of the face powder is preferably to be made accessible. Also, the opening 20 is made triangular so as to permit a neat construction compatible, 90 however, with exposing a sufficiently large surface of the compact face powder. The material of the face members 16 is depressed adjacent the opening 20 so as to extend downwardly and obliquely to the compact face powder and abut thereagainst thus forming a triangular well with the top of the compact face powder at the bottom of the well, and the depressed portions 20^a of the opening 20 as the walls 105 thereof. Similarly, the material about the opening 21 is depressed angularly as at 21^a so as to provide a conically shaped well in the same manner.

60 A powder puff 22 of such shape and dimensions as to fit into the opening 20, and a powder puff 23 of such dimensions

as to fit into the opening 21 are provided for each of the cosmetics.

It will thus be seen that there is provided a device in which the several objects of this invention are achieved and which is well adapted to meet the conditions of practical use.

As various possible embodiments might be made of the above invention and as 10 various changes might be made in the embodiment above set forth, it is to be understood that all matter herein set forth or shown in the accompanying drawings is to be interpreted as illustrative and not in a 15 limiting sense.

Having thus described my invention, I claim as new and desire to secure by Letters Patent:

1. In a vanity case of the character described, a container, a cover for said container and a guard member disposed and fitted to occupy the entire container, said guard member comprising a shaped piece of light material having a top face extending to the 20 walls of the container, and a plurality of openings in said top face depressed therefrom adapted to hold cosmetics, the edges of 25 said openings being chamfered.

2. In a vanity case, a container, a cover for 30 said container, a plurality of cosmetics held in said container, and a guard member fitted around the cosmetics, said guard member having openings therein wherethrough the cosmetics are made accessible, the edges 35 of said openings being chamfered to facilitate reaching the cosmetics.

3. In a vanity case, a container, a cover for 35 the container, a plurality of cosmetics held in the container, a powder puff for each cosmetic, and a guard member fitted around the cosmetics and the powder puffs, said 40 guard member having openings therein

wherethrough the cosmetics are made accessible, the edges of said openings being chamfered to facilitate reaching the cosmetics and 45 to form holders for said puffs whereby the latter when in place effect a closure for said openings.

4. In a vanity case, a rectangular container, a cover for said container in combination with a guard member disposed and fitted to occupy the entire container, said guard member having a triangular shaped opening of substantially half the container space, two sides of the triangular opening 50 extending parallel to two adjacent sides of the container and a circular opening in the adjacent portion of said member, said openings being adapted to hold cosmetics.

5. In a vanity case, a rectangular container, a cover for said container and a guard member disposed and fitted to occupy the entire container, said guard member having a triangular shaped opening of substantially 55 half the container space and a circular opening in the adjacent portion thereof adapted to hold cosmetics, the edges of said opening being chamfered to facilitate reaching the cosmetics and adapted to form a holder for the powder puffs whereby the latter when 60 in place effect a closure for said openings.

6. In a vanity case of the character described, a rectangular container, a cover for said container, and a guard member disposed and fitted to occupy the entire container, said guard member comprising a shaped piece of light material having a top face extending to the walls of the container and having a triangular and circular opening, 75 adapted to hold cosmetics, two sides of said triangular opening extending parallel to two adjacent sides of said guard member.

In testimony whereof I affix my signature.

CHARLES LIONEL MARCUS.
